CLAIM

The ornamental design for annular cleating for an athletic shoe, as shown and described.

DESCRIPTION

FIG. 1 is a perspective view of an annular cleating for an athletic shoe showing my new design; FIG. 2 is a bottom plan view;

FIG. 3 is a right side elevational view; and FIG. 4 is a perspective view of an annular cleating for an athletic shoe showing a modified form of my new design.

The broken line showing of a shoe and sole is for illustrative purposes and forms no part of the claimed design.

FIG. 1

FIG. 4

FIG. 2

FIG. 3

UNITED STATES PATENT AND TRADEMARK OFFICE
CERTIFICATE OF CORRECTION

PATENT NO. : Des. 299,084

DATED : December 27, 1988

INVENTOR(S) : Michael L. Tanel

It is certified that error appears in the above-identified patent and that said Letters Patent is hereby corrected as shown below:

In the Description, line 2, change "show" to --shoe--.

Signed and Sealed this
Fourteenth Day of November, 1989

Attest:

JEFFREY M. SAMUELS

Attesting Officer

Acting Commissioner of Patents and Trademarks
